GRIPPING DEVICE

Edward B. Cooper, Glen Ridge, and Maurice L. Macht, Jersey City, N. J., assignors to E. I. du Pont de Nemours & Company, Wilmington, Del., a corporation of Delaware

Application February 21, 1944, Serial No. 523,216

3 Claims. (CL. 89—35)

This invention relates to an improved gripping device and, more particularly, to an improved link for ammunition belts.

Heretofore, links made of a plastic material have been employed in ammunition belts which are used with self-fed, automatic, repeating guns such as machine guns. Ammunition belts using such links are formed with the cartridges acting as the pintles of the belt and the cartridges are ejected and the belt disintegrates as firing of the gun progresses. Difficulty has been encountered with the links heretofore available in that there is a tendency for the cartridges to work loose in the links when the ammunition belts are subjected to conditions of high humidity and, further, repeated torsional stress of the ammunition belts under tensional loads likewise tends to work the cartridges loose, this being known as "walking out" of the cartridges.

An object of the present invention is to provide an improved gripping device, particularly a link for ammunition belts. A further object is to provide a plastic link for ammunition belts which will hold cartridges securely regardless of atmospheric conditions or any ordinary stresses to which the ammunition belt may be subjected in use. Other objects will be apparent from the description of the invention given hereinafter.

The above objects are accomplished according to the present invention by providing a link for ammunition belts which link is formed of a plastic of high rigidity, form stability, and toughness, and comprises a body member, a pair of annular cartridge receiving rings in axial alignment, spaced from each other and rigidly interconnected by the body member, an offset annular ring rigidly connected to the body member between the pair of cartridge receiving rings and providing the connecting means to a similar succeeding link, each of the cartridge receiving rings having a plurality of longitudinal cantilever members for engaging an inserted cartridge and each of the cantilever members extending slightly inwardly to a point whose distance from the center of the ring is less than the radius of the cartridge to be inserted.

In a preferred embodiment of the invention, each cantilever member of each of the pair of cartridge receiving rings extends inwardly to a point whose distance from the center of the ring is less than the radius of the cartridge to be inserted, to at least such extent that the free end of the cantilever member, when in cartridge gripping position, is displaced from its idle position a distance which is a substantial multiple of the

distance its point of support may be displaced from the center of the ring by the expansive effect of water absorption on the ring. Further, the offset annular ring is preferably slotted as will be described hereinafter.

While the link of the present invention when made of any suitable plastic, is designed to overcome difficulties encountered with links heretofore available, the selection of the plastic is, nevertheless, important in providing a link best adapted for use in ammunition belts. It is preferred that the link should be made of a plastic having the following properties:

Rigidity.—The modulus of elasticity in tension, as determined by ASTM method D638—42T, should be at least 300,000 lbs. per square inch;

Form stability.—A test piece of the plastic subjected at 100° F. in air saturated with moisture, to a continuous flexural load which develops in the piece a maximum fiber stress of 1,000 lbs. per square inch, should suffer therefrom no more than negligible permanent deformation;

Toughness.—The hand-break number, determined as described in Modern Plastics, volume 21, No. 3, page 118 (November 1943) should be at least 90.

Among the plastics meeting the above requirements are certain synthetic linear polymers, some of which do not require any modification and others of which need to be compounded with appropriate auxiliary ingredients. A preferred member of this group is the synthetic linear polymer polyhexamethylene adipamide which meets the above stated requirements when its intrinsic viscosity (as defined in Carothers U. S. Patent 2,137,235) is greater than 1.0.

Regardless of the specific plastic selected for use in the present invention, it should be a plastic characterized by high rigidity, form stability, and toughness, even though it may not fully meet the above stated requirements.

The invention will be more specifically described with reference to the accompanying drawing wherein:

Fig. 1 is a side elevation of a fragment of an ammunition belt in which are shown in operative position two links embodying a preferred form of the present invention;

Fig. 2 is a vertical section through one of the links shown in Fig. 1;

Fig. 3 is a perspective view of the link shown in Fig. 2;

Fig. 4 is an end elevation of the same link, looking in the direction of the arrows 4—4 in Fig. 2;

Fig. 5 is an end elevation of the same link, looking in the direction of the arrows 5-5 in Fig. 2.

The cartridge link of this invention is preferably a single integral plastic molding and comprises a body member 1, annular cartridge receiving rings 2 and 3 in axial alignment with each other, and an offset annular ring 4. Each of the rings is rigidly connected to the body member 1 with the cartridge receiving rings 2 and 3 separated from each other and with the offset ring 4 connected to the body member 1 at a point between the rings 2 and 3.

A fragment of an assembled ammunition belt is shown in Fig. 1. The cartridge 5 passes through the receiving rings 2 and 3 of one link and the offset ring 4 of the succeeding link and, hence, functions as a pintle to secure adjacent links of the belt to each other. As each cartridge of the ammunition belt reaches the machine gun mechanism, it is automatically withdrawn from the link carrying it and, of course, the link falls free and the ammunition belt disintegrates.

A feature of this invention resides in the construction of the cartridge receiving rings 2 and 3. Ring 2 is designed to fit around the neck of the cartridge and ring 3 to fit around the body of the cartridge, as shown clearly in Fig. 2. For convenient identification, they will be referred to as neck ring 2 and body ring 3, respectively. Both rings comprise a plurality of longitudinal cantilever members 6 adapted to grip the cartridge to be inserted. As shown more clearly in Figs. 2 and 3, each of these cantilever members 6 of each of the rings 2 and 3 extends slightly inwardly and it must reach a point whose distance from the center of the ring is less than the radius of the cartridge to be inserted so that, in cooperation with the other members 6 of the ring, it will grip and hold the cartridge securely. When a cartridge is inserted into a pair of these rings and pushed into gripping position, a considerable frictional resistance develops at the extremities of the cantilever members 6 which have been forcibly spread apart because of the diameter of the cartridge exceeding the inside diameter of the extremities of the cantilever members 6.

It is preferred to design the link according to this invention so that, when the cartridge has been inserted far enough to insure an adequate grip, the interior taper of the neck ring 2 matches that of the shoulder of the cartridge 5, as shown in Fig. 2, so that the distance each cartridge is inserted in its link will be controlled and a uniform ammunition belt will be obtained.

After the cartridge 5 has been inserted into rings 2 and 3, the deformation of the extremities of the cantilever members 6 is preferably such that each is displaced from its idle position by an amount much greater than the amount to which its supported end can be displaced by expansion of the ring resulting from water absorption by the plastic material of which the ring is made. As an illustration, a link made in accordance with the present invention, when placed over a cartridge, has the extremities of its cantilever members 6 displaced radially by about 0.040 inch. If the link is now placed in a highly humid atmosphere causing an expansion of the rings to yield an elongation of the periphery of each ring by about 0.19 inch, there results a radius expansion of about 0.0022 inch. This expansion will have no practical effect upon the flexural stresses inasmuch as 0.0022 inch is many times less than 0.040 inch. Since the deflection of each

cantilever member 6 is a substantial multiple of the distance its point of support is displaced from the center of the ring, the decrease in gripping strength will be negligible. The effects of temperature variations are similar to those of moisture absorption but of lesser importance. If the reverse phenomenon occurs, e. g., shrinking of the rings, the cantilever member 6 will be displaced slightly more but the net overall magnitude of gripping action will be only negligibly increased and the grip will not be objectionably tight.

It has been found that the application of repeated torsional stress to an ammunition belt held under tensional load tends to work the cartridges loose from their links as the result of force exerted by one link on the next one through the offset ring 4 which functions as the coupling between the two links. This offset ring 4 normally fits loosely on the cartridge but has a tendency to bind when under combined tensile and torsional stresses. At the same time the offset ring 4 binds on the cartridge, it pushes against the neck ring 2 of the succeeding link and forces that link slightly down the neck of the cartridge inserted therein with the result that the cartridge will work loose or "walk out" and possibly prevent operation of the machine gun.

This difficulty with the cartridge working out of the link has been overcome according to the present invention by providing the offset ring 4 with a slot 7 through its walls transverse to its axis and extending around its circumference to adjacent the portion adjoining the body member 1.

The provision of the slot 7 results in a binding of the cartridge on one side of the offset ring 4 while the other side of the offset ring 4 pushes against the next link. Therefore, instead of forcing the link off the cartridge, the force causes the slot 7 to partially close, the effort being expended in deforming the ring 4 rather than in moving the next link. In an offset ring $\frac{1}{2}$ inch wide, a $\frac{1}{8}$ inch slot has been found satisfactory. Ordinarily, the slot 7 is made approximately equidistant from the ends of the ring. In any event, the determination of the slot width and position is made on the basis of the force required to deform the slot which force should be substantially less than that required to move a link on the cartridge.

A further feature of the present invention is found in the design of the body ring 3 to facilitate the action of a pair of pawls in the machine gun mechanism which advances the ammunition belt. Difficulty heretofore encountered with the pawls slipping on the surface of the body ring has been eliminated by providing a pair of shoulders 8 (see Figs. 3 and 4) on the body ring 3. A further improvement in the design of the link eliminates buckling of the links as they pass through automatic link loading machines. This improvement consists in the strengthening member 9 made as an integral part of the body ring 3 (see Figs. 3 and 4) and a similar strengthening member 10 and two additional strengthening members 11, 11 made as an integral part of the neck ring 2 (see Figs. 3 and 5).

While the invention has been described with particular reference to the specific embodiment shown in the drawing, it will be understood that this is merely illustrative and that the design of the link may be varied considerably without departing from the scope of the invention. Fur-

ther, the gripping device of the present invention is not only useful as an ammunition belt link but generally where belts of the type herein described are used.

An advantage of the present invention is that it provides an improved link for ammunition belts that will function reliably under severe conditions of use. A particular advantage of the links of this invention is that they will grip cartridges securely regardless of atmospheric conditions and they eliminate the "walking out" of cartridges from ammunition belts. Further, the present links have a strength and rigidity which overcomes any tendency to buckle as the links are handled in automatic loading machinery.

As many apparently widely different embodiments of this invention may be made without departing from the spirit and scope thereof, it is to be understood that the invention is not limited to the specific embodiments thereof except as defined in the appended claims.

We claim:

1. A link for ammunition belts in which cartridges form the pintles of the belt, said link being formed of a plastic of high rigidity, form 25 stability, and toughness, and comprising a body member, a pair of annular cartridge receiving rings in axial alignment, spaced from each other and rigidly interconnected by said body member, an offset annular ring rigidly connected to said body member between said pair of cartridge receiving rings and providing a connecting means to a similar succeeding link, said offset ring being slotted transversely to its axis through its walls at a point approximately equidistant from its ends and around its circumference to adjacent the portion thereof adjoining said body member, each of said cartridge receiving rings comprising a plurality of longitudinal cantilever members for engaging an inserted cartridge and each of said cantilever members extending continuously slightly inwardly so that its free end is positioned at a point whose distance from the center of said ring is less than the radius of the cartridge to be inserted.

2. A link for ammunition belts in which cartridges form the pintles of the belt, said link being formed of a plastic of high rigidity, form stability, and toughness, and comprising a body member, a pair of annular cartridge receiving

rings in axial alignment, spaced from each other and rigidly interconnected by said body member, an offset annular ring rigidly connected to said body member between said pair of cartridge receiving rings and providing a connecting means to a similar succeeding link, said offset ring being slotted transversely to its axis through its walls at a point approximately equidistant from its ends and around its circumference to adjacent the portion thereof adjoining said body member, each of said cartridge receiving rings comprising a plurality of longitudinal cantilever members for engaging an inserted cartridge and each of said cantilever members extending continuously slightly inwardly so that its free end is positioned at a point whose distance from the center of said ring is less than the radius of the cartridge to be inserted, to at least such extent that the free end of said cantilever member, when in cartridge gripping position, is displaced from its idle position a distance which is a substantial multiple of the distance its point of support may be displaced from the center of said ring by the expansive effect of water absorption by said ring.

3. A link for ammunition belts in which cartridges form the pintles of the belt, said link being formed of polyhexamethylene adipamide having an intrinsic viscosity greater than 1.0, and said link comprising a body member, a pair of annular cartridge receiving rings in axial alignment, spaced from each other and rigidly interconnected by said body member, an offset annular ring rigidly connected to said body member between said pair of cartridge receiving rings and providing a connecting means to a similar succeeding link, said offset ring being slotted transversely to its axis through its walls at a point approximately equidistant from its ends and around its circumference to adjacent the portion thereof adjoining said body member, each of said cartridge receiving rings comprising a plurality of longitudinal cantilever members for engaging an inserted cartridge and each of said cantilever members extending continuously slightly inwardly so that its free end is positioned at a point whose distance from the center of said ring is less than the radius of the cartridge to be inserted.
